MOVING PICTURE TOY

Ethel M. Leigh, Lyndhurst, N. J.

Application November 9, 1945, Serial No. 627,703

3 Claims. (Cl. 46—1)

1

This invention relates in general to a toy, and in particular to a child's toy having movable tapes imprinted with figures.

It is an object of this invention to provide a child's toy, comprising movable tapes bearing a series of pictures or the like.

It is another object of this invention to provide a child's toy comprising tapes bearing a series of imprints and adapted to be withdrawn from and retracted into a case.

Further objects of the invention as well as the construction, use, and operation thereof will in part be obvious and will in part be apparent from the following disclosure.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the toy constructed in accordance with the present invention.

Fig. 2 is a cross-sectional view through the toy.

Fig. 3 is an enlarged partial sectional view taken on the line 3—3 of Fig. 1.

Fig. 4 is a perspective view of the core of the toy, per se.

Fig. 5 is a perspective view of the axle, per se.

Fig. 6 is an exploded perspective view of the ends of the multiple tape.

In accordance with the present invention, the toy 10 includes a multiple tape 11 mounted in a case 12 and adapted to be withdrawn from and retracted into the case. On the tape are a series of figures 13, for example, outline pictures of various animals, birds and the like. At the end of the multiple tape 11 there is a pull handle, such as a strap 14 in the shape of a loop, mounted on a bar 15 or the like which serves to prevent the tape 11 from being pulled entirely into the case 12.

The case 12 comprises a narrow cylindrical body having substantially round flat sides and a cylindrical edge. At one position in the edge of the case 12 there is a slot 17 through which the multiple tape 11 passes.

The toy further includes a core 18 having a notched centerbore 19, see Fig. 4, to receive the ends of an axle 16, as shown in Fig. 5, having ridges 16a adapted to fit in the notches of the centerbore 19 of the core 18. The multiple tape 11 comprises separate superimposed tapes 11a and 11b.

2

11b and cut in the edge of the core 18 there are a plurality of notches 30 and 30a which are shaped to receive keys 31 and 31a mounted on the ends of the tape members 11a and 11b. Notch 30 extends substantially or completely across the width of the core 18, while the notches 30a extend from either side of the core 18 substantially but not completely to the center of the core, so that a bridge 30b separates these notches.

10 The axle 16 shown in Fig. 5, has, in addition to the ridges 16a along its surface, a key 32 at each end, which keys 32 mate with sockets 33 in the sides of the case 12 (see Fig. 3). Each socket 33 is mounted on a spring 20 whereby it may be turned within its mounting around a pivot means such as, for example, pivot pin 34 on which the socket is rotatably mounted. Thus, when the axle 16 is inserted in the case 12, its keys 32 mate with the sockets 33 whereby the axle 16 is rotatably mounted within the case.

15 The end of the tape member 11a (see Fig. 6) is secured to the key 31, for example, by means of glue or other adhesive, or by means of tacks, nails, or the like. This key 31 is adapted to fit in the notch 30 on the core 18, whereby the tape member 11a is replaceably mounted on the core. The tape member 11a, see Fig. 6, has a line 35 along its center which divides the design in half. Along one half of the tape member 11a lies the 20 second tape member 11b which for example, is a transparent tape having a complementary design thereon to complete the design on tape member 11a. This second tape member 11b is likewise mounted on a key 31a. This second key, like the tape member 11b is only half the width of key 31. Thus, key 31a is adapted to fit into either of the notches 30a on the core, whereby the tape member 11b is positioned along either half of tape member 11a.

25 As shown in Fig. 1, the outer end of each tape member 11a and 11b is provided with a bar 15 and strap 14 to be simultaneously gripped for pulling the tape members 11a and 11b from the slot 17 in the casing 12.

30 In the assembled toy shown partially in Fig. 3, the core 18 is mounted on the axle 16, which in turn is mounted in the sockets 33. The core 18 is thereby controlled by the spring 20 which controls the socket. A pin 36, or other conventional 35 release mechanism serves to hold the core 18 releasably stationary or to permit it to rotate inside the case 12. The multiple tape 11 which is wound around the outside of the core 18, see Fig. 2, can thus be pulled out and withdrawn into the case 50 55 12.

It is noted that in the device shown the tape, the core, the axle, or the case are all independently replaceable, so that the design and features of the device are completely variable. For example, a series of complementary tape members 11^a and 11^b may be prepared, and these series interchanged to give infinite variety to the toy. The line 35 formed in the tape member 11^a is provided by forming the tape member 11^a with a central lengthwise crease through its entire length to act as a guide for properly positioning the tape member 11^b on the tape member 11^a.

The pictures or design on the tape has been described only in general terms. It is understood that this design may be either pictures, such as, for example, pictures in outline or detail showing animals, birds, fish and the like, either fanciful or realistic. Similarly, there may be scenic pictures, cartoons, writing, or other designs imprinted on the tape. As set forth in the description of the figures, the design may be printed, cut-out, or otherwise imprinted on the tape. For example, the design may be engraved into the surface of the tape, or it may be raised thereon; it may be solid, or it may be cut out; it may be black and white, or it may be in color. According to one preferred form of the invention, the design comprises a series of fancifully designed animals in blue, pink, red and other colors particularly attractive to children.

The design may be a simple design, merely positioned on the tape, or it may be so positioned thereon that the motion of the tape causes a simulated motion of the design. For example, when animals are used in the design, the motion of the tape will cause the animals to appear to be running into or out of the case. Similarly a design may be arranged in a cartoon-like sequence, in which case a story is unfolded as the tape is drawn from the case. Likewise a printed word may be on the tape so that the story is read by drawing the tape from the case.

The design of the tape will fit the toy for almost any age group of children. This feature of the toy is particularly useful in connection with the replaceable core and tape, in which case one single toy with a plurality of tapes may alternately be a toy for a very young child and then for an older child.

In addition, the feature of sound may be added to the toy by means of a clapper or sounding ratchet on the core or otherwise. This completes the variety of the toy, providing sound, as well as motion and color on the toy. With these features, the toy appeals to practically the entire range of senses which serve to amuse children.

It is to be understood that the multiple tape 11 may be pulled out of the case 12 either toward the right or left, also that the tape 11 may be interchanged or serviced by removing one or both of the side walls of the case 12.

While I have illustrated and described the preferred embodiments of my invention, it is to be

understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A tape toy comprising a plurality of separate non-adhering tapes mounted upon a single core within a case and being superimposedly wound around said core mounted within said case, said core being rotatably mounted in the case, such mounting including a spring for the purpose of automatically retracting said tapes, said tapes having complementary designs thereon, and at least one of said tapes being transparent and at least one of said tapes having a pull member mounted on the end of the tape, whereby the tape may be retractably pulled from the case.

2. A tape toy comprising a plurality of separate non-adhering tapes mounted upon a single core within a case and being superimposedly wound around said core mounted within said case, said core being rotatably mounted in the case, such mounting including a spring for the purpose of automatically retracting said tapes, said tapes having complementary designs thereon, one of said tapes being substantially half the width of the other of said tapes and being transparent whereby the other of said tapes may be viewed therethrough, and at least one of said tapes having a pull member mounted on the end of the tape, whereby the tape may be retractably pulled from the case.

3. A tape toy comprising a plurality of separate non-adhering tapes mounted upon a single core within a case and being superimposedly wound around said core mounted within said case, said core being rotatably mounted in the case, such mounting including a spring for the purpose of automatically retracting said tapes, said tapes having complementary designs thereon, one of said tapes being substantially half the width of the other of said tapes and being transparent whereby the other of said tapes may be viewed therethrough and the other tape having a central lengthwise crease through its entire length as a guide for said first tape, and at least one of said tapes having a pull member mounted on the end of the tape, whereby the tape may be retractably pulled from the case.
